UNITED STATES PATENT OFFICE.

EDWARD N. TRUMP, OF SYRACUSE, NEW YORK.

CAR.

No. 831,492.

Specification of Letters Patent.

Patented Sept. 18, 1906.

Original application filed December 7, 1897, Serial No. 661,083. Divided and this application filed March 24, 1902. Serial No. 99,750.

To all whom it may concern:

Be it known that I, EDWARD N. TRUMP, of Syracuse, in the county of Onondaga and State of New York, have invented a certain 5 new and useful Car, of which the following is a specification.

My invention has for its object the production of a car which is particularly applicable for use in the apparatus for receiving and 10 conveying coke and similar materials set forth in my prior patent, No. 695,970, dated March 25, 1902, of the application for which patent this case is a divisional part; and it 15 consists in the novel combinations and constructions hereinafter set forth and claimed.

In describing this invention reference is had to the accompanying drawings, in which like characters designate corresponding parts in all the views.

20 Figure 1 is an elevation of my car, its cover being removed, a portion of a coke-oven, and the plunger for discharging the coke from the oven to the car. Fig. 2 is a vertical section taken on line 2 2, Fig. 1, the cover of the 25 car being shown in its inoperative position. Fig. 3 is an elevation of the detached means for causing the automatic discharge from the car of the coke or other material.

My car is illustrated in the accompanying 30 drawings in operative relation to parts of the apparatus for receiving and conveying coke set forth in my aforesaid patent. Said apparatus comprises the car A, forming the subject-matter of my present application, coke-35 ovens B, a plunger C for discharging the coke from the ovens B in a substantially horizontal plane upon the car A, means for moving the car to the desired locality, and means D for causing the automatic discharge of the 40 coke from the car. The parts B and C, which are of any suitable construction, are shown herein in order that the construction and operation of my car may be more readily apparent; but as said parts form no feature of 45 the present invention it is thought unnecessary to describe the same.

As preferably constructed the car A comprises supporting-wheels, a frame a, and a body provided with an inclined bottom a', 50 longitudinal and end retaining-walls a², and a cover a³. The supporting-wheels and the frame a are of any desirable form, size, and construction. Said bottom a' is of substantially the full width of the car, is arranged 55 with its longitudinal side edges disposed at

substantially right angles to the axes of the supporting-wheels in planes substantially perpendicular to said axes and parallel to the line of draft of the car, and is inclined upwardly from one longitudinal side edge to the 60 opposite edge. The lower longitudinal side portion of the bottom a' extends laterally beyond the tread of the supporting-wheels and preferably forms one of the sides of the base of the car, and the upper edge of the other 65 longitudinal side portion of said bottom forms one of the side edges of the top of the car.

The single longitudinal retaining-wall a² extends upwardly from the lower portion of the bottom a' and at substantially right angles 70 thereto and is provided with one or more lateral discharge openings, doors, or gates a⁴ for controlling said openings and catches or fastening means a⁵ for holding the doors or gates a⁴ closed. Said doors or gates a⁴ are usually 75 hinged at their upper edges to the main body of the car and open outwardly at their lower portions. The catches or fastening means a⁵ may be of any desirable form, size, and construction, the ones illustrated having their 80 intermediate portions pivoted at a⁶ beneath the body of the car at the outer sides of the doors or gates a⁴ and having their outer ends weighted and their opposite ends arranged normally in the path of the lower portions of 85 the doors or gates a⁴ and engaged with such lower portions. Said catches or fastening means a⁵ are readily forced from their operative position by elevating their outer weighted ends, and as the doors or gates a⁴ move into 90 their normal position the upper or inner ends of the catches or fastening means a⁵ are depressed by the lower edges of the doors or gates a⁴ and are automatically elevated into 95 their operative position by the weighted ends of said catches or fastening means.

The cover a³, which may be omitted, if desired, is hinged at its outer side to the longitudinal edge of the car-body opposite to the elevated longitudinal edge of the bottom a' 100 on an axis arranged at substantially right angles to the axes of the supporting-wheels and is movable on said axis toward and from the inclined bottom a'.

The means D preferably consists of a fixed 105 guide or rail which is arranged in proximity to a suitable chute or other receptacle (not illustrated) and is supported independently of the car in position to contact with and elevate the outer weighted ends or projecting 110

engaging parts of the catches or fastening means α^5 , and thereby force the same from operative position, whereupon the coke discharges automatically through the lateral discharge-openings.

5 The construction and operation of my car will now be readily understood upon reference to the foregoing description and the accompanying drawings, and it will be apparent to those skilled in the art that more or less change may be made in the component parts thereof without departing from the spirit of my invention.

Having thus fully described my invention, 15 what I claim as new, and desire to secure by Letters Patent, is—

1. In a car, the combination of a frame, supporting-wheels, and a body provided with a bottom inclined upwardly from one side of 20 the body to the opposite side of said body, the upper and lower side edges of the bottom being disposed at substantially right angles to the axes of the supporting-wheels, substantially as and for the purpose described.

25 2. In a car, the combination of a frame, supporting-wheels, and a body provided with a bottom formed of substantially the full width of the car and inclined upwardly from one side of the body to the opposite side of 30 said body, the upper and lower side edges of the bottom being disposed at substantially right angles to the axes of the supporting-wheels, substantially as and for the purpose specified.

35 3. In a car, the combination of a frame, supporting-wheels, and a body provided with a bottom having its longitudinal sides disposed at substantially right angles to the axes of the supporting-wheels, said bottom 40 being inclined upwardly from one of said sides and having one longitudinal side portion arranged at one side of the base of the car, and its other longitudinal side portion arranged at the opposite side of the top of the 45 car, substantially as and for the purpose set forth.

50 4. In a car, the combination of a frame, supporting-wheels, and a body provided with a bottom having its longitudinal sides disposed at substantially right angles to the axes of the supporting-wheels, said bottom being inclined upwardly from one of said sides and having its lower longitudinal side portion forming one of the sides of the base 55 of the car and the upper edge of its other longitudinal side portion forming one of the side edges of the top of the car, substantially as and for the purpose described.

60 5. In a car, the combination of a frame, supporting-wheels, and a body provided with a bottom formed of substantially the full width of the car and inclined upwardly, the lower edge of the bottom being arranged in a vertical plane substantially perpendicular to 65 the axes of the wheels, and the lower portion

of said bottom being extended laterally beyond the tread of the wheels, substantially as and for the purpose specified.

6. In a car, the combination of a frame, supporting-wheels, a body provided with a bottom inclined upwardly from one side of the body to the opposite side of said body, the upper and lower longitudinal edges of the bottom being disposed at substantially right angles to the axes of the supporting-wheels, said body being also provided with a longitudinal retaining-wall extending upwardly from the lower portion of said bottom, and having a lateral discharge-opening and a movable door or gate for said opening, and fastening means for holding the door closed, substantially as and for the purpose set forth. 70

7. In a car, the combination of a frame, supporting-wheels, and a body provided with a bottom formed of substantially the full width of the car and inclined upwardly, the lower edge of the bottom being arranged in a vertical plane substantially perpendicular to the axes of the wheels, and the lower portion of said bottom being extended laterally beyond the tread of the wheels, said body being also provided with a longitudinal retaining-wall extending upwardly from the lower portion of said bottom at substantially right angles thereto, and having a lateral discharge-opening, and a movable door or gate for said opening, substantially as and for the purpose set forth. 75

8. In a car, the combination of a frame, supporting-wheels, a body provided with a bottom inclined upwardly from one side of the body to the opposite side of said body, the upper and lower side edges of the bottom being disposed at substantially right angles to the axes of the supporting-wheels, and a 80 cover hinged to the longitudinal side of the body opposite to the elevated side edge of the bottom on an axis arranged at substantially right angles to the axes of the supporting-wheels, and movable on said axis toward and from the inclined bottom, substantially as and for the purpose described. 85

9. A car provided with an inclined bottom, the upper edge thereof forming one of the upper edges of the car, said edge extending in a direction parallel to the line of draft of the car, and a cover hinged to one longitudinal edge of the car on an axis substantially parallel to the path of movement of the car and movable on said axis toward and from the inclined bottom, substantially as and for the purpose specified. 90

10. In a car, the combination of a frame, supporting-wheels, a body provided with a bottom inclined upwardly from one side of the body to the opposite side of said body, the upper and lower side edges of the bottom being disposed at substantially right angles to the axes of the supporting-wheels, said body being also provided with a longitudinal 105

5 retaining-wall extending upwardly from the lower portion of said bottom and having a lateral discharge-opening and a movable door or gate for said opening, fastening means for holding the door closed, and means in position to contact with the fastening means for forcing said fastening means from operative position, substantially as and for the purpose set forth.

In testimony whereof I have hereunto signed my name, in the presence of two attesting witnesses, at Syracuse, in the county of Onondaga, in the State of New York, this 14th day of March, 1902.

EDWARD N. TRUMP.
